MEANS FOR APPLYING HEAT TO THE
WATER TUBES OF BOILERS

Thorvald A. Solberg, United States Navy

Application January 31, 1938, Serial No. 187,875

7 Claims. (Cl. 122—235)

(Granted under the act of March 3, 1883, as
amended April 30, 1928; 370 O. G. 757)

This invention relates to a method and means for applying heat to the water tubes of boilers. Essentially, all of the heat of combustion which heats the water until the same may be transposed into steam is applied by conduction through the metal walls which confine the water and/or steam, and which walls for highest efficiency usually are in the form of a plurality of spaced apart tubes. According to long teachings and practices in this art the great volume of the combustion heat is applied to such walls or tubes by convection, and very little of such volume has been applied to such walls or tubes by means of radiation from the combusting fuel to such walls or tubes. Furthermore, such teachings and practice inculcate and proceed upon the theory that in the conventional type of water tube boiler a substantial increase in the rate at which steam is made may be obtained only by increasing the number of the water tubes and by accelerating the velocity at which the hot combustion gases pass over such walls or between the water tubes.

The primary purpose of this invention is to accomplish the transfer of heat to water in a boiler for the purpose of making steam, and to do it in such a way as will result in the use of a lesser number of tubes than that used in the conventional boiler. Primarily, therefore, the amount of water evaporated per square foot of heating surface will be increased over that obtained in conventional type boilers, and thereby will result in boilers having less weight, smaller size, and consequently less maintenance cost.

A further object of the invention, resulting from the above, is to require less space for the combustion of fuel, and to provide a boiler having a higher operating efficiency than that of other similar designs. The objects of this invention are realized by providing the arrangement of the boiler heating surfaces so that a larger proportion of these surfaces will be subjected to the radiant heat of the furnace, which in turn will require a lesser number of tubes not exposed to the radiant heat, inasmuch as a greater proportion of the heating value of the fuel after combustion will have been absorbed by the surface exposed to radiant heat.

The general principle of such arrangements consists of designing the fireside rows of the tube nest in patterns which essentially form one or more arches, or tapering projections, which extend from the normal tube nest toward the furnace or combustion chamber of the boiler. These designs or patterns, in addition to increasing the amount of surface subjected to radiant heat in-

corporated in the usual type of boiler, furthermore are designed in such a way as to more evenly distribute the mass flow of the hot gases through the tube nest. The design of these patterns also is such that the radiant heat may penetrate further into the body of the tube bank than in the conventional type of boiler. 5

A further and equally important object of this invention is to improve the transfer of heat from the hot gases to the boiler tubes by convection in those areas of the boiler where all heat transfer occurs in this manner, namely, in the body of the tube bank, which is not exposed to radiant heat energy. This object is accomplished by arranging the tube patterns in those sections of the boiler so that the areas available for gas passage become progressively less as gases proceed through the boiler from the furnace to the stack. The purpose of this arrangement is to provide a gradually decreasing area to compensate for the gradual decrease in volume of the gases of combustion, which decrease in volume is incident to the gradual decrease in temperature of these gases as their heat is removed in passing from one row of tubes to the next. This feature further results in a diminution of the amount of heating surface required in the convection portions of the boiler, inasmuch as the consequent higher average gas velocity through this portion of the tube bank, as compared with that of conventional boilers, results in a greater amount of heat transfer. It further should be noted that the design of tube pattern for the convection portions of the boiler is such as to provide a more even distribution of the mass flow of the gases of combustion, which results in all portions of the boiler doing the same amount of work. 30 35

The invention herein described is applicable not only to boilers being newly designed, but in many cases is equally applicable to boilers already built and in use, which boilers could be improved by removing some tubes and thereby modifying the tube patterns, as shown for example in Figures 3 and 4 of the drawings. 40 45

With the foregoing and other objects in view, the invention consists in the construction, combination and arrangement of parts hereinafter described and illustrated in the drawings, in which, 50

Fig. 1 is a diagrammatic sectional view of a tube nest arrangement according to this invention.

Fig. 2 is a cross-section of an individual boiler tube. 55

Fig. 3 is a diagrammatic sectional view of another tube nest embodying this invention.

Fig. 4 is a diagrammatic sectional view of still another tube nest in accordance with this invention, and

Fig. 5 is a diagrammatic sectional view showing that part of the tube nest receiving its heat by convection, showing the decreasing spacing between the tubes.

10 There is shown at 10 the furnace walls with the customary refractory lining 11, between which are placed the boiler tubes 12 above the fire bed and grates (not shown).

As shown in Fig. 1, in accordance with this 15 invention, the number of tubes increase progressively in an upward direction from the fire bed. The tubes are also arranged so that the maximum number of tubes are exposed to radiation both from the fire bed and from the refractory lining 20 11. To effect this, there is provided outermost curved vertical rows 14 commencing adjacent the lining 11 and curving inwardly. Spaced from this row is a next inner curved row 15 containing a lesser number of tubes, and spaced therefrom is 25 a next inner row 16 with a still lesser number of tubes, followed by succeeding rows 17 and 18, it being observed that the lowermost tube of each succeeding row is further from the fire bed than that of the prior row.

30 Next to this group of five, more or less, successively shorter curved rows 14 to 18 comes a cluster of tubes in the form of a spearhead and consisting of two rows 19 and 20, curved away from each other, the base of the spearhead being formed by a diamond shaped group 21. Next to the spearhead rows 19 and 20 comes another group of curved rows 22, 23, 24 and 25, each row having successively less tubes. A center cluster or spearhead of rows 26 and 27 with a diamond 35 shaped group 28 therein joins the tubes extending symmetrically towards the other wall of the furnace.

Inward from the tubes of rows 14 to 28, inclusive, and in symmetrical continuation there- 45 of is the row of tubes 29. Beyond the row of tubes 29 is a row of tubes 30, in which the tubes are located in spaced pairs. A similar row of tubes 31 thereabove has its pairs located partly above the spaces between the pairs in row of tubes 30. Next beyond comes an indefinite number of rows of tubes 32, sufficient in number to absorb all the efficient heat carried by the combustion gases on the way to the chimney.

With the above arrangement, it will be ap- 55 parent that the maximum number of tubes are exposed to the radiant heat from the fire bed and from the refractory linings 11, as well as the reradiation from the hottest tubes nearest the fire bed, and further, that this arrangement 60 also takes advantage of the maximum convection of the combustion gases, for the variation in the spaces between the tubes also provides decreasing gas path area as the gases progressively cool and contract as they give up their 65 heat to the successive tubes in the path of the combustion gases through the boiler.

In Figs. 3 and 4, there are shown two arrangements embodying this invention as applied to already existing boiler tube patterns. In conventional patterns, the tubes are in closely spaced staggered rows. By sacrificing certain tubes, some convection efficiency may be lost, but such loss, if any, is more than compensated by the great increase in radiant heat absorbing efficiency, as well as increased convection absorbing

efficiency resulting from increased velocity of the combustion gases through the tube nest. In conventional patterns as the gases cool and contract in passing through the nest the efficiency of heat absorption is progressively lowered by the reduction in gas velocity.

In Fig. 3, the tubes 30 of the two lowermost rows are spaced substantially apart, by omitting every second and third tube, while at the center, several additional tubes are omitted. The next 10 inner row of tubes 31 has the outermost tube omitted, thus placing this row of tubes 31 in staggered relation to the tubes of the row below. The same principle is followed for the next successive rows of tubes 32, 33 and 34, while rows of 15 tubes 35, 36 and 37 have tubes commencing more closely to the lining 11 as shown, but also have at least every second and third tube omitted. The two topmost rows of tubes 38 may be conventionally positioned. At the center, a heart-shaped recess 39 is provided by omitting such additional tubes as necessary. The omission of the tubes, as thus described, provides increased surfaces which are exposed to radiation from the furnace as well as gas paths or lanes speed- 20 ing up the velocity of the combustion gases and equalizing their flow therethrough.

In Fig. 4, the principles of this invention have been applied to a conventional pattern by omitting sufficient tubes in the lowermost three rows 30 of tubes to provide triangular spearheaded clusters 40.

In Fig. 5, the principles of this invention are carried out by placing the tubes 41 in the lowermost row a substantial distance apart, and gradually decreasing both the horizontal and the vertical spacing of the tubes from the bottom to the top.

Other modifications and changes in the proportions and arrangements of the parts may be made 40 by those skilled in the art without departing from the nature of the invention, within the scope of what is hereinafter claimed.

The invention described herein may be manufactured and used by or for the Government 45 of the United States of America for governmental purposes without the payment of any royalties thereon or therefor.

Having thus set forth and disclosed the nature of this invention, what is claimed is:

1. A boiler tube pattern consisting of a plurality of rows of tubes, the tubes in successively ascending rows being spaced more closely together to provide gas lanes therethrough of gradually decreasing area, the gas lanes curving in 55 the direction of the center of the pattern.

2. A boiler tube pattern consisting of a plurality of rows of tubes, the tubes in successively ascending rows being spaced more closely together to provide gas lanes therethrough of gradually decreasing area, the gas lanes leading in the direction of the center of the pattern to thereby provide a maximum area of tube surface exposed to radiant energy, and to counteract the otherwise decreasing velocity of the gases as they contract in giving up their energy to the lower tubes.

3. A boiler tube pattern consisting of a plurality of rows of tubes of substantially equal 70 length, the number of tubes in successively ascending rows gradually increasing to a maximum and being more closely spaced apart from the lower to the upper tubes in vertically curving rows, thus providing a maximum amount 75

of tube area exposed to radiant energy and also gas lanes of gradually decreasing area through the tubes counteracting the decreasing velocity of the cooling, contracting gases passing therethrough.

5 4. A boiler tube pattern consisting of a plurality of rows of tubes, the number of tubes in successively ascending rows gradually increasing to a maximum, the gas lanes curving and 10 tapering in the direction of the center of the pattern.

15 5. A boiler tube pattern consisting of a plurality of rows of tubes, the number of tubes in successively ascending rows gradually increasing to a maximum, the gas lanes curving and tapering in the direction of the center of the pattern to thereby provide a maximum area of tube 20 surface exposed to radiant energy, and to counteract the otherwise decreasing velocity of the

gases as they contract in giving up their energy to the lower tubes.

6. A boiler tube pattern consisting of a plurality of rows of tubes, the tubes in successively ascending rows being spaced more closely together to provide curved gas lanes therethrough of gradually decreasing area, whereby the draft loss through the banks will be a minimum and the heat absorption from the combustion and combustion products will be a maximum.

10 7. A boiler tube pattern consisting of a plurality of rows of tubes, the tubes in successively ascending rows being spaced more closely together to provide curved gas lanes therethrough of gradually decreasing area, whereby combined heat absorption from radiation and convection will be a maximum with the minimum possible number of tubes and the minimum possible heat absorbing surface.
